UNITED STATES PATENT OFFICE.

WALTER J. ROWLEY AND JOHN G. ALBRIGHT, OF PITTSBURGH, PENNSYLVANIA.

SHAVING-BRUSH.

1,009,583.

Specification of Letters Patent. Patented Nov. 21, 1911.

Application filed March 14, 1911. Serial No. 614,411.

To all whom it may concern:

Be it known that we, WALTER J. ROWLEY and JOHN G. ALBRIGHT, citizens of the United States of America, residing at North 5 Side, Pittsburgh, in the county of Allegheny and State of Pennsylvania, have invented certain new and useful Improvements in Shaving-Brushes, of which the following is a specification, reference being 10 had therein to the accompanying drawing.

This invention relates to shaving brushes and the objects of the invention are to provide a brush with an adjustable and yieldable shield for preventing lather, soap and 15 water from getting on the hand when the brush is being used, and to furnish a brush with a shield that can be shifted into engagement with the bristles of a brush to prevent the bristles from spreading when dry- 20 ing and to confine the bristles to provide a pointed end on the brush as is desired when placing lather on the upper lip.

We attain the above objects by a mechanical construction that will be hereinafter specifically described and then claimed.

Reference will now be had to the drawing, wherein:

Figure 1 is a side elevation of the brush showing the shell partly broken away and 30 partly in section and shifted on to the bristles, and Fig. 2 is a similar view showing the shield on the body of the brush.

A brush in accordance with this invention comprises a cylindrical body 1 having one 35 end thereof provided with a handle 2 and the opposite end with bristles 3, these three elements being of the ordinary and well known type common to shaving brushes. The body 1 adjacent to the handle 2 is provided with an annular groove 4.

The shield comprises a frusto-conical shaped yieldable shell 5 preferably made of rubber. The lower edges of the shell 5 are reinforced or provided with a rim 6 and the 45 upper edges thereof are provided with an inwardly projecting flange 7 adapted to engage in the groove 4.

When the shield is shifted from the body to the bristles 3 it is frictionally held by 50 said bristles. With the shield upon the body 1 an annular compartment 9 is formed around the body 1 and this compartment receives any lather or water that is forced

rearwardly upon the body 1 and the shield prevents the lather or water from contacting 55 with the hand.

Owing to the fact that the material of which the shield or attachment is formed is relatively thin in cross-section and yieldable or flexible, it will be understood that 60 the annular flange 7 is expanded for the purpose of inserting the attachment on the brush with the flange within the groove, and that, when moved down onto the bristles of the brush, the outer periphery 65 of the attachment may be grasped along its rear portion to cause the flange to provide a pressure on the bristles to permit the shield or attachment to act to remove the lather which, owing to the fact that the pocket 70 which is formed in advance of said flange and which is open to the bristles at all points in advance of the flange, will be retained within said pocket and prevent its passing onto the hand of the user. The 75 fact that the pocket is open to the bristles and that the part which acts on the bristles is located at the rear or bottom of the pocket, insures the elimination of any liability of splashing of the lather or material carried 80 by the bristles as the shield passes thereover.

One embodiment of the invention has been described and we reserve the right to make such changes as fall within the scope of the appended claim.

What we claim is:

A removable attachment for shaving brushes, comprising an annulus formed of relatively thin flexible material and frusto-conical in form, said annulus having its end 90 of larger diameter peripherally reinforced and having its end of smaller diameter formed with an inturned flange, the relative diameters of the ends of the annulus permitting it to be mounted in position on a 95 shaving brush with its end of larger diameter extending over, but exerting no material pressure on the bristles of the brush.

In testimony whereof we affix our signatures in the presence of two witnesses.

WALTER J. ROWLEY.
JOHN G. ALBRIGHT.
